TELEPHONE JUNCTION BOX COVER

Allen A. Foster, Jr., 477 W. Loma Alta, and John M. Velardo, 495 W. Loma Alta, both of Altadena, Calif.

Filed Apr. 11, 1962, Ser. No. 69,673

Term of patent 14 years

(Cl. D26—14)

FIG. 1

FIG. 2

FIG. 3

FIG. 4

FIG. 1 is a top plan view of a telephone junction box cover showing our new design;

FIG. 2 is a side elevational view thereof;

FIG. 3 is an end view as seen from the left of FIG. 1; and

FIG. 4 is an end view as seen from the right of FIG. 1. We claim:

The ornamental design for a telephone junction box cover, as shown.
